UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING AND LOADING APPARATUS.

Application filed October 24, 1921, Serial No. 509,981. Renewed November 28, 1927.

My invention relates to mining and loading apparatus wherein the main frame is held stationary while the dislodging mechanism operates to mine coal from an upright mine wall for delivery to loading apparatus in position to receive it adjacent the place of dislodgement, and one of the objects of the invention is the provision of simple improved apparatus of this character to efficiently mine and load coal directly from a coal mine vein.

A further object of the invention is the provision of improved operating mechanism for that type of dislodging means which comprises dislodging tools which are rigidly connected to a supporting frame to move bodily therewith.

Another object of the invention is the provision of automatic limit stop mechanism for the feeding and restoring apparatus of the dislodging mechanism.

A further object of the invention is the provision of a system of hydraulic anchoring apparatus particularly adapted for that type of mining machine in which the main frame is held stationary while the supplemental frame is moved relatively thereto to carry bodily therewith digging and splitting tools.

Other objects of the invention will appear hereinafter, the novel features and combinations being set forth in the appended claims.

In the accompanying drawings—

Fig. 1 is a plan view of my improved mining machine and a part of the loading apparatus;

Fig. 2 is a central longitudinal sectional view of Fig. 1;

Fig. 3 is a plan view of the complete mining and loading machine;

Fig. 4 is a sectional elevation taken on the line 4—4 of Fig. 3 looking in the direction of the arrows;

Fig. 5 is an elevational view of the mining and loading machine shown in Fig. 3, with one of the wall jacks omitted;

Fig. 6 is an end elevation of the dislodging mechanism;

Fig. 7 is a sectional detail of the connection between the forward conveyor and the side conveyor of the mining and loading machine;

Fig. 8 is a sectional detail view taken on the line 8—8 of Fig. 1 looking in the direction of the arrows;

Fig. 9 is a sectional elevation on the line 65 9—9 of Fig. 3 looking in the direction of the arrows;

Fig. 10 is a sectional view taken on the line 10—10 of Fig. 1 looking in the direction of the arrows;

Fig. 11 is an enlarged detail view of the releasing means for the pawl and ratchet mechanism shown in Fig. 1;

Fig. 12 is an enlarged sectional elevation of a portion of Fig. 11;

Fig. 13 is a detailed sectional elevation of Fig. 1 taken on the line 13—13;

Fig. 14 is a plan view of Fig. 13; and

Fig. 15 is a diagrammatic illustration of the system of hydraulic anchor controlling 70 mechanism.

By referring to Figs. 1 and 2 it will be seen that to the rear end of the main frame 16 is connected an electric motor 17, the shaft of which carries a worm 18 which is in mesh with the worm gear 19. As shown in Fig. 9, the motor shaft 20 is keyed to the worm 18 and the worm gear 19 is integral with the gear 21, and both the worm gear 19 and the gear 21 are mounted on the vertical shaft 22, which in turn is mounted on the main frame. As shown in Figs. 1 and 2, the gear 21 meshes with the large spur gear 23 which is keyed to the vertical shaft 24 journaled in suitable bearings 25 and 26 in the main frame 16. Secured to the upper end of the shaft 24 is an eccentric 27 for operating the feeding means of the dislodging mechanism hereinafter described.

The forward bottom portion 28 of the main frame is curved, as shown in Fig. 2, to facilitate sliding of the machine over the mine floor. Above the forward base portion 29 of the main frame is a cylinder 30 for receiving the plunger 31 of a hydraulic roof jack for anchoring the main frame. This hydraulic roof jack comprises a shoe 32 having an upper serrated surface 33 and a lower bowl-shaped bottom 34 fitting into the dish-shaped recess 35 in the upper end of the 100 plunger 31.

The cylinder 30 is provided with a cylindrical outer surface to serve as a supporting standard and also as a cylindrical bearing for the hub 36 of the arm or supplemental frame 37 to which the dislodging mechanism is rigidly connected for bodily movement therewith.

The hub 36 is provided on its upper peripheral portion with ratchet teeth 38, as shown in Fig. 1. Surrounding the ratchet teeth is a ring 39 which carries a series of pivoted pawls 40 preferably extending approximately entirely around the hub 36.

The pawl and ratchet mechanism is shown in detail in Fig. 11. The pawls 40 are pivoted to the ring 39, the same being spaced-apart and arranged in series almost entirely around the ring 39. These pawls are each urged by its spring into engagement with the notches between the ratchet teeth, as shown in Fig. 11. When the ring 39 together with the pawls carried thereby is oscillated back and forth by means of the eccentric 27 the pawls 40 will move the hub 36 in feeding direction when the ring 39 is moved in a clockwise direction, and when the latter is retracted the pawls 40 will be permitted by the springs 41 to ride over the ratchets into the next notches.

By referring to Fig. 1 it will be seen that the ring 39 is provided with a rearwardly extending yoke 42 which is provided with a rectangular opening 43, the side walls of which are engaged by the plate 44, at the center of which is located the eccentric 27. Therefore when the motor 17 is operated to rotate the eccentric 27 in an anti-clockwise direction, as viewed in Fig. 1, the plate 44 will be moved back and forth in the rectangular opening 43 in the yoke 42. At the same time the plate 44 will be oscillated laterally which will effect oscillation of the yoke 42 and the ring 39, and when the latter is oscillated the pawls 40 will be moved forward and backward to effect continuous forward rotation, step by step, of the hub 36 and therefore of the arm 37 and the dislodging mechanism mounted on the outer end of this arm.

In order to lock the arm 37 against retrograde movement when the pawls 40 are retracted a spring-pressed pawl 45 is mounted on the standard 46 which is secured at 47 to the main frame 16, as shown in Fig. 2. This spring-pressed pawl 45 is similar in construction to the spring-pressed pawl 40 shown in Fig. 11, but since the pawl 45 is mounted substantially on the main frame it acts as an abutment to prevent retrograde movement of the ratchet ring 36 after the latter has been moved forward a step.

The dislodging mechanism is shown in Figs. 3, 5 and 6 as secured to the outer end of the arm 37 by means of the bolts 48 and 49. The dislodging mechanism may therefore be adjusted radially to various positions along the arm 37 relative to the upright central axis of the bearing standard 30. This adjustment may be effected by loosening the bolts 48 and 49 shown in Figs. 3 and 5 and manually sliding the splitting tool frame 55 along the arm 37 after which the bolts 48

and 49 may again be tightened to secure the dislodging mechanism in adjusted position.

The dislodging mechanism comprises a frame 50 to which are rigidly attached the penetrating and splitting tools 51, 52, that designated 51 being located at the floor, and that designated 52 being located midway between the floor and roof in advance of the floor dislodging device 51. Intermediate the dislodging tools 51 and 52 are piercing tools 53 for the purpose of trimming off the ragged wall left by the main splitting tools. At the floor are additional trimming piercing implements 54 secured rigidly to the frame 50.

At the upper portion of the frame 50 are spaced-apart rearwardly extending arms 55 and 56, as shown in Fig. 3. To the rear ends of these arms and between the same is pivoted at 57 an arm 58 which carries at 85 its outer end the roof splitting tool 59. Secured to the arm 58 are roof trimming piercing implements 60, as shown in Figs. 3, 5 and 6. These roof trimming tools may be mounted on an auxiliary arm 61 pivotally connected at 62 to the arm 58 so as to be adjusted on an axis at right angles to the radial arm 37. After the adjustment is made the bolt 63 may be relied upon to hold the arm 61 in adjusted position relative to the arm 58. After the arm 58 has been moved to adjusted position the bolt the head of which is shown at 64 in Fig. 3 may be used in connection with the nut 65 to hold this arm in adjusted position. However, it is preferred to provide a hydraulic motor 66 comprising a cylinder with a piston 67 therein and a piston rod 68 connected by a link 69 to the arm 58 for adjusting the elevation of this arm and locking it in adjusted position.

Secured at 70 to the arm 58 is an arcuate guide 71 which is adapted to move along the arcuate guideway 72 for reinforcing the dislodging tool 59. Mounted on the 110 arcuate bar 71 are wall trimming devices 73, as shown in Fig. 6.

Connected at 74 to the arm 37 is a spring 75 adapted to engage an overhanging downward extension 76 from the plate 77 which is mounted on top of the hub 36 and pivotally connected at 78 to the upper end of the cylinder 30. The plate 77 is of sufficient diameter to extend over a portion of the ring 39, as shown in Figs. 1 and 2. The plate 77 is connected by a plurality of spaced-apart pin and slot connections, as shown at 79, 80 and 81 in Fig. 1. These pin and slot connections may each be constructed as shown in Figs. 13 and 14. A bolt 82 is secured to the ring 39 and is provided with a collar 83 so that a washer 84 may rest on the loop-shaped seat 85. The collar 83 may be guided along the slot 86 and the friction between the washer 84 and 130

the seat 85 regulated so that the plate 77 may have a circumferential sliding movement relatively to the ring 39.

Therefore when the spring tripping device 75 engages the abutment 76 the plate 77 will be moved circumferentially relatively to the plate 39 a distance equal to the length of the slot 86 in the plate 77.

This circumferential movement of the plate 77 to a limited extent relatively to the ring 39 is for the purpose of operating a series of cams 87, one of which is shown enlarged in Fig. 11. These cams are located on the bottom of the plate 77 in spaced relation corresponding to the respective pawls 40, there being also a similar cam 87' for the pawl 45 shown in Fig. 2. Each of the pawls 40 and the pawl 45 is provided with a lever as shown at 88 in Fig. 11. These levers are secured to the pawls and extend upwardly into the cams 87. Therefore when the plate 77 is automatically shifted upon the dislodging mechanism reaching the limit of its feeding movement, the levers 88 are operated to throw the pawls out of engagement with the ratchet teeth and thereby free the arm 36 for restoring movement in reverse direction to initial position.

When desired all of the pawls may be thrown out of engagement with the ratchet teeth by means of the lever 89 shown in Fig. 1 which is secured to the plate 77, as shown in Figs. 1 and 8. When the plate 77 is shifted circumferentially relatively to the ring 39 as permitted by the pin and slot connections 79, 80 and 81 the spring-pressed pin 90 is forced out of its notch 91, and upon reaching the notch 92 will snap into the same to hold the plate 77 in its shifted position so that the pawls 40 will remain in released position during the return of the arm 37 to initial position. By moving the lever 89 in the opposite or clockwise direction the pin 90 may be moved back into the notch 91, whereupon the pawls will be restored to and held in their ratchet engaging positions.

In order to return the arm 37 together with the dislodging mechanism mounted thereon to initial position after such dislodging mechanism has completed its stroke of approximately 180°, power driven mechanism is provided by mounting a gear wheel 93 at the lower end of the hub 36, as shown in Fig. 2, and connecting to this gear wheel 93 a pinion 94 which is connected to the motor 17 by a train of gearing. As shown in Fig. 2, the spur gear 94 carries a beveled gear 95 which meshes with another beveled gear 96 which is connected to the forward end of the shaft 97. As shown in Fig. 10, this shaft 97 is keyed to a worm gear 98 which is located at the rear portion of the main frame 16, as shown in Fig. 1. Meshing with the worm gear 98 is a worm 99

on the vertical shaft 100. At the lower end of this shaft 100 is a spur gear 101 which meshes with the large gear 23 to receive power therefrom. As shown in Figs. 1, 9 and 10, a clutch 102 is mounted on the shaft 97 so as to connect the gear 98 to the shaft 97. It can readily be seen by referring to Fig. 10 that since the gear 98 is loose on the shaft 97 the throwing in of the clutch 102 will transmit power from the gear 98 to the shaft 97 and thus effect rotation of the arm 37 in a clockwise direction through the train of gearing comprising the beveled gears 95 and 96 and the spur gears 94 and 93. In order to automatically stop the restoring movement imparted to the arm 37 I have provided a cross-rod 103 in position to be struck by the arm 37 when the latter reaches its initial position. This cross-rod 103 is pivoted at 104 to a bell crank lever 105 which is pivoted to the main frame 16 at 106. A rod 107 connects the bell crank lever 105 to the clutch element 102'. It will thus be seen that the clutch may be moved to released position either by means of the handle 108 or by means of the arm 37 automatically engaging the rod 103.

The loading apparatus comprises an endless conveyer 109 which has spaced-apart flights 110 adapted to travel over the semi-circular ring receiving plate 111, as shown in Figs. 1 and 3. The forward edge of the plate 111 may be beveled, as shown at 112, and this semi-circular ring plate may be hinged to the sides of the base 29, as indicated at 113 in Fig. 5, and the upright cylindrical surface 114 provided as a bearing for the sprocket chain 115. This sprocket chain meshes with a sprocket 116 at the bottom of the vertical shaft 24, as shown in Fig. 2. Therefore when the eccentric 27 is driven anti-clockwise, the flights 110 will be moved circumferentially along the receiving plate 111 toward the receiving end of the lateral conveyer 117, as shown in Fig. 3. The forward lower end of the conveyer 117 may be inclined downwardly at 118 and then extended horizontally at 119 to the forward beveled edge 120, as shown in Figs. 3 and 7. The rearward extension on the horizontal flat portion 119 may be provided at 121 and a portion of the inclined scoop of the conveyer provided with a hinged section 122 for permitting the flights 110 to readily pass under such hinged section. The edges of the flights 110 are beveled, as shown at 123 and 124, so that when the flights 110 ride over the plate 122 they may readily pass under the hinged section 122 and cause the lower end of the latter to scrape the material off the flights and thus keep such material from passing rearwardly with the flights.

The conveyer 117 may be of the endless

chain scraper type comprising a stationary bed 125 and scrapers 126 traveling over the same.

The lateral conveyer 117 may be supported on brackets 127 and 128 hinged at 129 and 130, respectively, to one side of the motor and one side of the main frame 16. Suitable lugs may be provided for holding the brackets 127 and 128 in horizontal position, as shown in Fig. 4. The brackets 127 and 128 are detachable and the conveyer 117 removable when desired. Additional support to the conveyer 117 may also be given by the wall jack 131 which is hinged at 132 to the ears 133 extending from one side of the motor 17.

In addition to the wall jack 131 other wall jacks, such as those designated 134 and 135, may be provided. The horizontal hydraulic jack 134 is pivoted at 136 to ears extending rearwardly from one corner of the motor frame. The horizontal hydraulic jack 135 is pivoted at 137 to ears extending from a lateral intermediate portion of the main frame. The horizontal hydraulic jacks 134 and 135 are also provided with roof jacks 138 and 139, respectively, as shown more clearly in Fig. 15. The hydraulic jack 135 may be located in the dotted line position 140, as shown in Fig. 3, when the entire machine is to be moved forward to a new location, but when the dislodging mechanism is being operated the hydraulic jack 135 may be moved to the position shown in full lines in Fig. 3 to act as a wall jack. The hydraulic jacks 131, 134 and 135 cooperate with the forward roof jack 32 to hold the framework of the mining machine securely in stationary position during the operation of the dislodging mechanism.

As shown in Fig. 9, the upper end of the vertical shaft 100 is provided with an eccentric cam 141 for engaging the eccentric strap 142 which is connected to the plunger 143 of a hydraulic motor 144 for pumping liquid from the tank 145 into the pressure supply pipe 146.

Fig. 15 represents more or less diagrammatically the system of hydraulic circuits and connections and the control mechanism therefor. When the pump plunger 143 is reciprocated by the mechanism shown in Fig. 9, liquid may be drawn from the tank 145 and forced into the pressure supply pipe 146 in accordance with the control permitted by the check valves 147 and 148. By means of the valve 149 the hydraulic jack 131 may be operated to wall-engaging position or retracted therefrom. The valve 149 may also be moved to such position as to lock the wall jack 131 in its adjusted position.

By means of the valve 150 the hydraulic jack 134 may be given horizontal movements, but it should be noted that the connections 65 are such that when pressure is directed into

the horizontal cylinder the roof jack 138 is at the same time moved to anchoring position. When the valve 150 is in the position shown in Fig. 15, the pressure supply pipe 146 is connected to the cylinder 134 to the right of piston 152. When the valve 150 is given a quarter turn to the right by means of the lever 153, the pressure pipe 151 is connected to the cylinder 134 to the left of the piston 152 and the pipe 154 is connected to the pipe 155 which leads to the exhaust pipe 156. Therefore the roof jack 138 may be released and moved toward the right to a new position when desired.

In a similar manner the valve 157 may be actuated to control the operation of the wall jack 135 and the roof jack 139.

By means of the valves 158 and 159 the hydraulic motor on the dislodging mechanism may be operated to adjust the position of the arm 58 and lock the latter in adjusted position.

By means of the valve 160 hydraulic pressure may be directed into the cylinder 30 through the passage 161 to move the plunger 31 upwardly so that the shoe 32 will engage the roof. When the valve 160 is in the position shown in Fig. 15, the cylinder 30 is connected to the exhaust pipe 156, but when the lever 162 is given a quarter turn to the right the pressure supply pipe 146 will be connected to the cylinder 30. When this occurs the pressure medium will flow from the pipe 163 into the cylinder 164 of the accumulator 165, the latter comprising a plunger 166 having a collar 167 engaging a strong spring 168. It is preferred to include the accumulator 165 in the system because the operation of the dislodging tools may cause slight vibrations tending to effect a yielding of the roof or floor to the pressure of the forward roof jack. When this yielding action tends to take place the accumulator will immediately act to cause the plunger 31 to move the required distance to maintain the desired anchoring action, even though the valve 160 may be moved to such position as to lock the plunger 31 in its roof-engaging position.

At the rear end of the motor frame is secured an upright floor jack 169, as shown in Fig. 5. By referring to Fig. 15 it will be seen that a valve 170 controls the operation of this floor jack either to lift or lower the rear end of the main frame on the curved bottom 28 as a fulcrum. When the inclination of the machine has been adjusted by means of the floor jack, the valve 170 may be moved to such a position that the piston 171 in the cylinder will be locked in adjusted position, after which the plunger 172 may slide over the mine floor and act as the rear support for the mining and loading machine.

I claim:

1. In a mining machine, the combination

- with a main frame, of a supplemental frame mounted thereon for swinging relatively thereto on an upright axis, a radial arm on said supplemental frame, dislodging mechanism carried by said radial arm for bodily movement therewith in position to operate on the upright solid face of a coal vein, and power transmission mechanism between said main and supplemental frames comprising a 5 circular ratchet and a multiplicity of pawls distributed around the same to swing said supplemental frame on said upright axis to effect the operation of said dislodging mechanism.
- 10 2. In a mining machine, the combination with dislodging mechanism, of a frame for supporting the same, a plurality of pawl and ratchet devices for feeding said dislodging mechanism, oscillatory mechanism to operate said pawl and ratchet devices, and means for rendering inoperative at will said pawl and ratchet devices.
- 15 3. In a mining machine, the combination with dislodging mechanism, of a plurality of pawl and ratchet devices for operating said dislodging mechanism, means for operating said pawl and ratchet devices to effect feeding of said dislodging mechanism, and manually operated means for releasing the 20 pawl and ratchet devices to permit restoration of said dislodging mechanism to initial position.
- 30 4. In a mining machine, the combination with a main frame, of a supplemental frame mounted thereon to swing relatively thereto, dislodging mechanism mounted on said supplemental frame to move bodily therewith and comprising spaced-apart penetrating wedging tools adapted to penetrate the solid coal face of a mine vein and split coal therefrom in large pieces, pawl and ratchet mechanism comprising an arcuate ratchet and a 35 multiplicity of spaced-apart pawls distributed along the same for powerfully feeding said dislodging mechanism by swinging movement of said supplemental frame relatively to said main frame, and oscillatory means for operating said pawl and ratchet mechanism to effect such powerful feeding of 40 said dislodging mechanism.
- 45 5. In a mining machine, the combination with a main frame, of a supplemental frame mounted thereon for swinging movement relatively thereto, dislodging mechanism mounted on said supplemental frame to move bodily therewith and adapted to penetrate the solid face of a mine vein and split large pieces of mineral therefrom, a driven 50 shaft, an eccentric mounted thereon to rotate therewith, and means comprising a multiplicity of spaced-apart pawls connected between said eccentric and said supplemental frame for swinging the latter to effect the 55 operation of said dislodging mechanism.
- 60 6. In a mining machine, the combination with a main frame, of a supplemental frame mounted thereon for arcuate movement relatively thereto, dislodging mechanism mounted on said supplemental frame in position to operate on an upright mine wall while said main frame rests on the mine floor, a ring separate from said supplemental frame, pawl and ratchet mechanism between said ring and said supplemental frame, and means for oscillating said ring to operate 70 said pawl and ratchet mechanism to transmit feeding movement to said dislodging mechanism.
- 75 7. In a mining machine, the combination with a main frame, of a supplemental frame mounted thereon for swinging movement relatively thereto on an upright axis and comprising a circular hub, dislodging mechanism mounted on said supplemental frame to move bodily therewith and comprising a 80 penetrating and wedging tool adapted to act on the solid coal face of the mine vein and split large pieces of coal therefrom over a wide area by a continuous forward movement, oscillating driving mechanism, and slip clutch mechanism comprising a multiplicity of distributed pawls between said driving mechanism and said hub to effect step-by-step forward feeding movement of 85 said dislodging mechanism.
- 90 8. In a mining machine, the combination with supporting framework, of dislodging mechanism comprising a clawlike penetrating and wedging tool adapted to enter the solid face of the coal vein and split large 95 pieces of coal from the unmined mass by a continuous forward feeding movement along an arcuate path of travel, and power transmission mechanism comprising a ratchet and a multiplicity of spaced-apart pawls for feeding the dislodging mechanism while 100 said supporting framework remains stationary to secure a powerful continuous forward movement of said claw-like penetrating and wedging tool.
- 105 9. In a mining machine, the combination with a main frame, of a supplemental frame mounted on said main frame for arcuate movement relatively thereto, dislodging mechanism mounted on said supplemental frame for movement therewith, a tertiary frame, pawl and ratchet mechanism between said tertiary frame, and said supplemental frame and comprising a multiplicity of 110 pawls, means for operating said tertiary frame to cause said pawl and ratchet mechanism to effect feeding of said dislodging mechanism, and cam operated mechanism for rendering inoperative the pawl and ratchet mechanism to permit restoration of 115 said supplemental frame and said dislodging mechanism.
- 120 10. In a mining machine, the combination with supporting framework, of dislodging mechanism mounted thereon and comprising 125
- 130

- ing a series of spaced-apart pointed penetrating wedging tools adapted to penetrate the solid face of a coal vein and tear large pieces of coal from its native bed,
- 5 3 feeding mechanism comprising a multiplicity of pawl and ratchet devices distributively connected to said dislodging mechanism, means on said framework for driving said feeding mechanism, and means for holding 10 said framework stationary while said dislodging mechanism is operated by power distributively transmitted through said pawl and ratchet devices.
11. In a mining machine, the combination 15 with a main frame, of a supplemental frame mounted on said main frame for arcuate movement relatively thereto, dislodging mechanism adapted to operate on the upright solid face of a mine vein, means for 20 mounting said dislodging mechanism on said supplemental frame for movement therewith horizontally in advance of said main frame while connected thereto for continuous engagement with the upright face of 25 the coal vein during feeding movements continuously forward through an angle of about 180° from one side of the said main frame to the other, and means comprising widely distributed clutch mechanism for imparting 30 step by step forward movements to said supplemental frame to operate said dislodging mechanism while said main frame remains stationary.
12. In a mining machine, the combination 35 with a main frame, of a supplemental frame mounted thereon to swing relatively thereto, dislodging mechanism on said supplemental frame in position to act on the upright face of a coal vein horizontally in advance of said main frame, means comprising a multiplicity of distributed pawl and ratchet devices for imparting a continuous forward feeding movement to said supplemental frame by frequent increments to operate 40 said dislodging mechanism, and means for preventing retrograde movement of said dislodging mechanism after increments of forward movement thereof.
- 45 13. In a mining machine, the combination 50 with supporting framework, of dislodging mechanism mounted thereon in position to operate on the upright working face of a coal vein, a plurality of distributed pawl and ratchet devices for feeding said dislodging mechanism, oscillatory mechanism, means on said framework for operating said oscillatory mechanism to effect the feeding of said dislodging mechanism, and means operable as a unit for rendering inoperative at will all of said pawl and ratchet devices to free said dislodging mechanism for return to initial position.
- 55 14. In a mining machine, the combination 60 with a supporting frame adapted to rest on and slide over a mine floor, of dislodging mechanism mounted thereon in position to operate on the upright face of a coal vein in advance of said frame, a plurality of distributed pawl and ratchet devices for operating said dislodging mechanism, means for operating said pawl and ratchet devices to effect feeding of said dislodging mechanism, and means for simultaneously releasing all of said pawl and ratchet devices to free said dislodging mechanism for restoration to initial position.
- 65 15. In a mining machine, the combination 70 with dislodging mechanism, of pawl and ratchet mechanism comprising a plurality of distributed pawls, means for operating said pawl and ratchet mechanism to effect feeding of said dislodging mechanism, and means comprising a plurality of cams one associated with each of said pawls for releasing all of the latter by a single operation.
- 75 16. In a mining machine, the combination 80 with dislodging mechanism, of means comprising pawl and ratchet mechanism for feeding said dislodging mechanism, said pawl and ratchet mechanism, a plurality of spaced-apart driving pawls and a retaining pawl all in engagement with the same ratchet, and means comprising a plurality of cams one for each of said pawls to release the latter to permit restoration of the 85 dislodging mechanism.
- 85 17. In a mining machine, the combination 90 with a supporting frame, of mining mechanism mounted thereon for operation on an upright mine wall in advance of said frame, 100 pawl and ratchet mechanism for feeding said mining mechanism, and limit stop mechanism for automatically releasing said pawl and ratchet mechanism to permit restoration of said mining mechanism to initial position.
- 95 18. In a mining machine, the combination 105 with a supporting frame, of dislodging mechanism mounted thereon in fixed relation therewith for operation on an upright mine wall in advance of said frame, step by step clutch mechanism for imparting powerful feeding movement to said dislodging mechanism to move the same along the mine wall parallel to the face thereof, limit stop 110 mechanism for automatically releasing said clutch mechanism to free said dislodging mechanism for restoring movement to initial position in readiness for another operation on the upright mine wall, gearing for 115 effecting a quick restoring movement of said dislodging mechanism to initial position, and additional limit stop mechanism for automatically discontinuing the transmission of power through said gearing.
- 120 19. In a mining machine, the combination 125 with a supporting frame, of dislodging mechanism mounted thereon in position to operate on an upright mine wall horizontal- 130 ly in advance of said frame, means for feed-

ing said dislodging mechanism comprising a ring, clutch mechanism within said ring for transmitting step-by-step feeding movement to said dislodging mechanism while 5 preventing retrograde movement thereof, and means for actuating said ring to secure such feeding movement for the dislodging mechanism to act on the upright mine wall in advance of the machine and while the 10 latter is supported on the mine floor.

20. In a mining and loading machine, the combination with a supporting frame having a rounded bottom at its forward end portion to facilitate sliding over the mine 15 floor, of dislodging mechanism mounted on

said frame for arcuate movement on an upright axis and in advance of said frame, a conveyer connected to the forward end of said frame for yielding engagement with the mine floor, means for operating said dislodging mechanism to dislodge material to be received by said conveyer, and means for sliding said frame over the floor while said conveyer is in yielding engagement therewith. 25

In testimony whereof I have signed my name to this specification on this 22d day of October, A. D. 1921.

EDMUND C. MORGAN.
